UNITED STATES PATENT OFFICE.

ANDREW N. WEIDENBACH, OF MITCHELL, SOUTH DAKOTA.

BOX-HOLDING CLAMP.

1,299,640.

Specification of Letters Patent. Patented Apr. 8, 1919.

Application filed June 1, 1918. Serial No. 237,774.

To all whom it may concern:

Be it known that I, ANDREW N. WEIDENBACH, a citizen of the United States, residing at Mitchell, in the county of Davison and 5 State of South Dakota, have invented certain new and useful Improvements in Box-Holding Clamps, of which the following is a specification, reference being had to the accompanying drawings.

10 This invention relates to work holders and particularly to certain improvements in that class of work holding machines in which a form is provided for supporting and clamping the side boards and bottom boards of 15 egg cases and like crates while they are being nailed.

The general object of this invention is to provide a work holding support adapted to be raised by means of a pedal and to be 20 rotated to a plurality of positions and to provide means whereby the work holding support may be held in its rotated positions so that when the support and work are lowered onto a table, the work will come down 25 flat on the table and thereby prevent the material being knocked out of place when the support is lowered onto the table.

Other objects have to do with improvements in the details of construction and arrangement of the several parts as will hereafter appear.

My invention is illustrated in the accompanying drawings, wherein:—

Figure 1 is a perspective view of a box forming machine containing my improvements;

Fig. 2 is a fragmentary longitudinal sectional view through the machine;

Fig. 3 is a section on the line 3—3 of 40 Fig. 2;

Fig. 4 is an end elevation showing the box support rotated to permit the nailing on of the sides of the box;

Fig. 5 is a section on the line 5—5 of 45 Fig. 2;

Fig. 6 is a section on the line 6—6 of Fig. 2; and

Fig. 7 is a perspective detail view of one 50 of the lifting rods and the trunnion of the box support.

Referring to these drawings, it will be seen that the supporting frame or table of the machine comprises the longitudinal beams 10, the vertical legs 11, the transverse boards 12, and the braces 13 and 14, the

last named braces extending between each pair of legs. One pair of legs is connected by a longitudinal brace 15 upon which a treadle 16 is hinged. Pivotaly supported from ears 17, attached in any suitable manner to the frame of the machine, are the levers 18, these levers at their adjacent ends being provided with a plurality of perforations 19 and being connected by links 20 to the treadle 16. The end pieces of the box which is to be formed are supported upon a holder comprising a longitudinally extending base 21. To one end of this base is affixed the end piece 22, while to the other end of the base is affixed the end piece 23, this end piece being cut away at its top, as at 24. Extending downward through slots in the end boards 12 are the lifting rods 25 which also extend down through slots in the cross pieces 13. These lifting rods are connected by a longitudinal bar 26 so that they will move in unison and are braced by angle irons 27. Links, preferably in the form of hooks 28, engage the ends of the bar 26 with the outer ends of the levers 18. It will thus be seen that when the treadle is depressed, the lifting rods 25 will move upward.

The lifting rods or standards 25 are connected to the box support by means of trunnions 29 which extend out from the end pieces 22 and 23 and pass through openings in the lifting rods. These trunnions have a cross bar 30 at their extremities, and mounted upon each lifting rod is an outwardly extending, resilient strip 31, formed at its upper end with cross depressions 32, in which the T-shaped head 30 or cross bar of the trunnion is adapted to engage. This strip 31 is somewhat resilient and the resilience of the strip urges its upper end outward so that the T-shaped head 30 of each trunnion is held securely in its adjusted position and against accidental rotation. The outer face of each of the members 22 and 23 is braced by a cross cleat 33 supported in position by irons 34 having outwardly turned upper extremities disposed beneath the corresponding cleat.

The member 23 constitutes a head for one end of the box body and for supporting the opposite end of the box. I provide a head 35 which is preferably adjustable toward or from the head 23. To this end, the head 35 is provided with angle irons 36, which are slotted and bolts 37 pass through these angle 110

irons and into the base 21. By this means, the head 35 may be shifted toward or from the head 23 to accommodate boxes of longer or shorter length. For the purpose of supporting the middle partition of the egg crate or box, I provide the head 38 which also is supported by angle irons 39, these angle irons being slotted and engaged with the base by means of bolts 40 so that the middle 10 partition may also be adjusted to suit longer or shorter boxes.

For the purpose of holding the end boards and partition board of the box in place against the heads, 23, 35 and 38, I provide 15 clamping plates 41 on the confronting faces of the heads 23 and 35. These clamping plates are outwardly deflected at their upper ends as at 42 and the lower ends are supported by means of spring actuated 20 hinges 43. The partition supporting head 38 coacts with a clamping plate 44 which is also outwardly deflected at its upper end and is connected by a hinge 45 to a supporting member 46 which at its lower end is 25 connected to a spring hinge 47. Preferably the outer edge faces of the heads 23 and 35 have attached to them the metallic strips 48, which extend down slightly below the upper face of the base 21, so as to 30 guide the adjustable heads, and preferably the base 21 is cut away on each side as at 49 to permit the partition board of the box to be properly adjusted. It is for this reason that the heads 23 and 35 are also cut away 35 as at 24 to permit the ready insertion and removal of the end boards of the box or crate. Preferably the upper faces of the boards 12 at a plurality of points are provided with metal reinforcing or wear strips 40 50, the under face of the base 21 being also provided with like wear strips 50 to rest upon the first named strips when the box support is lowered.

In the practical operation of this device, 45 the ends A of the crate are inserted between the clamps 41 and the heads 23 and 35, while a partition board B is inserted between the clamp 44 and the head 38. The bottom of the crate may now be readily nailed upon 50 the end boards and middle board of the crate and then the supporting frame is raised by depressing the pedal 16 and the box support is rotated a quarter of a revolution and again lowered, whereupon one of 55 the side boards may be nailed in place. The box support may be again raised and rotated to bring the other side uppermost and the opposite side of the crate may then be attached. The completed crate can then be 60 readily removed by simply lifting it off of the support and the device is ready to receive the boards of another crate.

By means of this invention, the box ele-

ments may be readily held in position while being nailed and the work of assembling the 65 parts of the crate and nailing them together is very greatly expedited and the accuracy of workmanship increased.

The T-shaped heads 30 coact with the 70 springs 31 to lock the movable form in its adjusted positions so that the form will come down flat on the table and not hit on the corner first and thereby knock the material out of place when the form is lowered onto the table.

Having described my invention, what I claim is:

1. A machine of the character described comprising a table, standards mounted upon the table for vertical movement, a box supporting frame mounted upon the standards and having trunnions extending through the standards whereby the supporting frame may be rotated in a plurality of positions with relation to the table, the standards being mounted for vertical movement whereby the box supported in said frame may be rested on the table in any one of the positions to which the supporting frame may be rotated, and means mounted on the standards for yieldingly holding the box supporting frame in a plurality of rotated positions such that the box supporting frame will rest flat upon the table when the standards are lowered.

2. A machine of the character described comprising a table, standards slidably mounted upon the table for vertical movement, a box supporting frame mounted upon the standards and having trunnions extending through the standards, whereby the supporting frame may be rotated into a plurality of positions with relation to the table, and resiliently yieldable means for locking the trunnions in a plurality of rotated positions.

3. A machine of the character described comprising a table, standards vertically slidably through the table, a box supporting frame mounted upon the standards and including end members having trunnions extending through the standards, the trunnions being T-shaped, and upwardly and outwardly extending resilient strips mounted upon the upper ends of the standards, each strip having crossed grooves upon its outer face, in which said T-shaped ends of the trunnions lock, whereby to hold the box supported frame in rotated positions.

In testimony whereof I hereunto affix my 120 signature in the presence of two witnesses.

ANDREW N. WEIDENBACH.
